UNITED STATES PATENT OFFICE.

LEVI C. GUNDERSON, OF BEAVER, UTAH.

BOILER FEED-WATER REGULATOR.

1,373,237.

Specification of Letters Patent. Patented Mar. 29, 1921.

Application filed February 16, 1920. Serial No. 353,907.

To all whom it may concern:

Be it known that I, LEVI C. GUNDERSON, a citizen of the United States, residing at Beaver, in the county of Beaver and State 5 of Utah, have invented new and useful Improvements in Boiler Feed-Water Regulators, of which the following is a specification.

This invention comprehends the provision 10 of a boiler feed water regulator by means of which the water in the boiler can be maintained at any height desired, thereby reducing the amount of fuel used, as the water may be maintained at a height to prevent 15 exploding or bursting of the boiler, and yet low enough to give the boiler maximum steam space.

To this end the invention embodies a tank 20 in communication with the boiler, the tank containing a float associated with a valve which controls the admittance of water from the supply pipe to the boiler, the float and valve being adjustably connected so that the water in the boiler may be maintained at 25 any desired level.

The nature and advantages of the invention will be better understood when the following detail description is taken in connection with the accompanying drawings, the 30 invention residing in the construction, combination and arrangement of parts as claimed.

In the drawings forming part of this specification like numerals of reference indicate 35 similar parts in the several views and wherein:

Figure 1 is a vertical sectional view through the regulator.

Fig. 2 is a transverse sectional view taken 40 on line 2—2 of Fig. 1.

Fig. 3 is a similar view taken on line 3—3 of Fig. 1.

Fig. 4 is a view in elevation of the stationary member of the valve.

Fig. 5 is a similar view of the movable part.

Fig. 6 is an end view of the latter.

Fig. 7 is a view similar to Fig. 4 of a modified form.

Fig. 8 is a vertical sectional view there- 50 through.

The feed regulator forming the subject matter of my invention comprises a tank 10 which may be of any suitable size, and above 55 which is supported a valve casing 11 secured to the tank by means of the arms 12. The

tank 10 communicates with the boiler 15 by means of the pipes 13 and 14 respectively. A water supply pipe 16 communicates with the casing 11 through the top thereof, while 60 communication between the casing 11 and the boiler 15 is established by means of the pipe 17. This communication is controlled by a float actuated valve to be presently described.

The valve is mounted in the casing 11 and comprises a stationary tubular member 18 in which is slidably fitted the tubular member 19. The outer tubular member 18 has its opposite ends tapered and frictionally held 65 in the bushings 20, the latter being threaded in central openings in spaced partitions 21 arranged within the casing 11. The respective members of the valve have openings 22, and when these openings register, the water 70 entering the inner member 19 from the supply pipe 16, passes into the casing 11 from where it is conveyed to the boiler through the opening 22, establishing communication between the casing 11 and the pipe 17. Obviously when the inner member 19 is in position whereby the openings of the respective members of the valve are out of registration the valve is closed and obviously cuts off the supply of water to the boiler. 75

For the purpose of controlling the adjustment of the movable member 19 of the valve, the latter is provided with a cross piece 24 with which one end of the rod 25 is connected. This rod has a threaded portion 26 80 which is screwed into the hollow stem 27 which is carried by the float 28 and slidably through the top of the tank 10. The rod 25 and the hollow stem 27 are both slidable through stuffing boxes 28. A lock nut 29 is 85 associated with the rod 25. The float 28 is slidably mounted upon guide rods 30 which maintains the float in proper position within the tank 10. By reason of the construction shown and described, it is manifest that 90 when the water in the boiler reaches a predetermined low level, the float 28 gravitates within the tank 10 and by reason of its connection with the movable member 19 of the valve, lowers the latter, bringing the open- 100 ings 20 thereof into registration with the similar openings of the outer stationary part of the valve 18. Consequently water from the supply pipe 16 passes through the registered openings into the tank 11, and from 110 the latter to the boiler through the pipe 17. The tank 10 is in communication with the

boiler by the pipes 13 and 14, respectively. As the level of the water in the boiler and tank reaches a predetermined high level, the float 28 is obviously raised, and the inner member 19 of the valve moved upwardly to a position whereby the openings 20 thereof are moved out of registration with the similar openings of the member 18. In this position of parts the valve is closed. The construction provides for an adjustment between the rod 25 of the valve and stem 27 of the float, and consequently the regulator can be adjusted to maintain the water in the boiler at any desired level. A set screw or the like 31 is carried by the stationary member 18 of the valve, while the movable member 19 is provided with a slot or groove 32 in which the set screw or projection 31 is fitted. This serves to guide the movable part of the valve in its movements, and also serves as a stop for the member 19 so that the valve is checked in its movements to both opened and closed positions.

It is to be understood that the movable member 19 of the valve is tightly fitted within the member 18 so as to prevent leakage. If desired, the movable member of the valve may be made as shown in the modified form of the invention, wherein the movable member 34 is embraced by a split band of yieldable material, such as rubber or the like 35. The member 34 is grooved for the reception of the band 35, while both of these parts are provided with alined openings 36 for registration with the openings above mentioned in the stationary part of the valve. In this instance the split band 35 is provided with the slot or groove 37 for the reception of the projection 31.

While it is believed that from the foregoing description, the nature and advantages of the invention will be apparent, I desire to have it understood that I do not

limit myself in this connection, and that such changes may be resorted to when desired as fall within the scope of what is claimed.

What is claimed is:

1. A water feed regulator for boilers comprising a tank communicating with the boiler, a casing communicating with the boiler and arranged above the tank, a water supply pipe leading into the casing, a valve controlling the communication between the casing and the supply pipe, said valve comprising inner and outer tubular members, said inner member being movable within the outer member, both of said members having openings adapted to register when the valve is opened, a float arranged within the tank and connected with the movable member of the valve, said movable member having a slot, and a projection carried by the outer member and fitted within the slot whereby the valve is limited in its movements to opened and closed positions.

2. A water feed regulator for boilers comprising a tank in connection with the boiler, a casing supported above the tank and in connection with the boiler, a water supply pipe communicating with the casing, spaced apertures arranged within the casing and having alined openings, bushings threaded in said openings, a valve including a stationary tubular member terminally fitted in said bushings, a second tubular member slidably fitted within the stationary tubular member, said tubular members having openings adapted to be brought into registration when the valve is open, a float operating within said tank, and a connection between the float and said second tubular member to guide the latter to automatically open and close the valve.

In testimony whereof I affix my signature. 85
LEVI C. GUNDERSON.
